UNITED STATES PATENT OFFICE.

WILLIAM P. RUDKIN, OF OKLAHOMA, OKLAHOMA.

GENERATOR.

1,328,016.

Specification of Letters Patent. Patented Jan. 13, 1920.

Application filed November 21, 1918. Serial No. 263,496.

To all whom it may concern:

Be it known that I, WILLIAM P. RUDKIN, a citizen of the United States, residing at Oklahoma, in the county of Oklahoma and 5 State of Oklahoma, have invented certain new and useful Improvements in Generators, of which the following is a specification.

The present invention appertains to improvements in gas generators, adapted particularly for use where a constant predetermined pressure of the gas is especially desired. I have found in the art of welding that generators of known type today used 10 for supplying gas to welding torches are more or less wasteful and unsatisfactory, mainly because the production of the gas while automatic, is subject to fluctuation to such an extent even as to result in poor 15 workmanship unless the operator of the torch is particularly expert in the art. In other words, as an incident to the automatic action of gas generation, whether procured through the dip or other well known process, the pressure of the gas steadily falls 20 from the maximum until the acetylene is brought into contact with the liquid or vice versa, and regeneration begins, whereupon there is a rapid rise in the pressure and 25 danger of excessive heat as a result. It is mainly to overcome this difficulty that my 30 invention has been devised and by means of which I am able to maintain what I term for the purposes of distinction a constant 35 differential pressure suitable to the particular work to be done.

To this end my invention lies in the provision of means for controlling the pressure which is operative to bring about that 40 association of the gas forming substances which results in the generation action.

These and such other objects as may hereinafter appear are attained by the novel construction, combination and arrangement 45 of parts to be hereinafter specifically described and claimed. Reference will now be had to the accompanying drawings forming a part of this specification, wherein:

The figure of the drawing is a sectional view of an embodiment of my invention.

Describing in detail the construction of this device, 1^a designates a tank or container to receive the water utilized for the generation of the gas. It might be noted at this 55 point that the apparatus involved is of the

dip type. At the top of the tank 1^a is the pressure control chamber 8^a. Centrally of the tank are disposed guide rods 20 between which is mounted the container 21 for the carbide, the outer surface of said container 60 having the rollers 22 for coöperation with the rods 20 to guide the movement of said container upwardly and downwardly in the operation of this apparatus.

A discharge passage 9^a extends upwardly 65 from the central bottom portion of the tank 1^a and into the central chamber 23 of the container 21, said passage passing outwardly of the tank to the storage receiver or service pipes. This passage, at 70 a suitable point, is provided with a cut-off valve 10^a and a by-pass 12^b establishes communication between the pipe 12^a which forms the continuation of the pipe 9^a and the pressure chamber 8^a. In this by-pass 75 is a cut-off valve 24 and a pressure indicator 25.

In charging the apparatus, the carbide container 21 is introduced into the tank by removal of the cover 26 and water is then 80 poured into the tank 1^a. Immediately gas generation takes place and proceeds until gas accumulates within the pressure chamber 23 sufficiently to raise the container 21 to an elevated position out of the water, 85 substantially as shown in the drawing. The pressure thus produced is admitted into the pressure chamber 8^a to provide pressure which will act upon the exterior of the container 21. The pressure being thus provided, the valve 24 is cut off and the container 21 descends, and gas generation again 90 takes place under automatic control and until sufficient pressure is developed in the central chamber 23 to effect the elevation 95 of the container 21 from the water in the tank. The pressure on the upper side of said container being constant it will give a constant feeding of gas from the central chamber at the pressure originally admitted 100 to chamber 8^a in the use of the apparatus.

At the base of the container 21 is provided a flange extension for the purpose of safeguarding against the water being entirely displaced from the casing by the 105 pressure of the gas, and the escape of the gas about the lower end of said casing.

Having thus described my invention, what I claim as new is:

1. A generator of the class described 110

comprising a closed liquid holding reservoir having a pressure chamber at the upper portion thereof, a container for holding gas generating material movably mounted for movement in the chamber, and means establishing communication between the pressure chamber and the container whereby to convey the gas between the chamber and the container, said container being shiftable into and out of the liquid in the reservoir under the control of the pressure in the pressure chamber.

2. A generator of the class described comprising a closed liquid holding reservoir having a pressure chamber at its upper portion, a container for holding gas generating material movably mounted for movement in the chamber and having a pressure receiving chamber, and means establishing communication between the pressure chamber of the reservoir and the pressure receiving chamber of the container whereby the gas pressure in the pressure chamber operates to control the position of the container with respect to the liquid in the reservoir.

3. A gas generator of the class described comprising a closed liquid holding reservoir having a pressure chamber at its upper

portion, a container for holding gas generating material movably mounted for movement in the chamber, guide means with which the container coacts, a discharge conduit for the gas in the pressure chamber, and a by-pass establishing communication between said gas discharge conduit and the movable container whereby the pressure is operable to effect raising and lowering of the container with respect to the liquid in the reservoir.

4. A gas generator of the class described comprising a liquid holding reservoir having a pressure chamber at its upper portion, a container for holding gas generating material movably mounted within the reservoir, guide means with which the container coacts, a discharge conduit for the gas in the pressure chamber, a by-pass establishing communication between said gas discharge conduit and the movable container whereby the pressure is operable to effect raising and lowering of the container with respect to the liquid in the reservoir, and regulatory means interposed in the conduit for controlling the admission of gas into the container.

In testimony whereof I affix my signature.

WILLIAM P. RUDKIN.
